LIQUID SCINTILLATION SPECTROMETER FOR DETERMINING RADIOACTIVITY LEVELS IN TEST SAMPLES

Frederick W. Thompson, Northfield, Ill., assignor to
Packard Instrument Company, Inc., Downers Grove,
Ill.

Filed Apr. 9, 1970, Ser. No. 22,344

Term of patent 14 years

Int. Cl. D24—02

U.S. Cl. D83—1

FIG. 1.

FIG. 3.

FIG. 2.

-fig. 4.

-fig. 5.

FIG. 1 is a perspective view of the liquid scintillation spectrometer for determining radioactivity levels in test samples cabinet showing my design;

FIG. 2 is a front elevational view;

FIG. 3 is a side elevational view;

FIG. 4 is a top plan view;

FIG. 5 is a rear elevational view.

The side of the liquid scintillation spectrometer for determining radioactivity levels in test samples not shown is a mirror image of the side shown.

I claim:

The ornamental design for a liquid scintillation spectrometer for determining radioactivity levels in test samples, substantially as shown and described.
